ATTORNEY.

UNITED STATES PATENT OFFICE.

FELIX SAMSON, OF NEW YORK, N. Y.

DESIGN FOR A NAP-SURFACE OF CLOTH.

SPECIFICATION forming part of Design No. 12,280, dated May 24, 1881.

Application filed February 19, 1881. Term of patent 7 years.

To all whom it may concern:

Be it known that I, FELIX SAMSON, of the city, county, and State of New York, have originated a novel Design for the Nap-Surface of Cloths, of which the following is a full, clear, and exact description, in connection with the accompanying drawing.

This design relates to that class of designs applicable to smooth-surfaced beaver or napped cloths on which the ornamental figuring is produced by cutting grooves into the pile or nap in the act of shearing the same, so as to form figures appearing in clear relief on the surface-texture of the cloth, such as shown in two patents issued to me February 15 and March 8, 1881. In one of the former designs the grooves were so disposed, both vertically and horizontally, on the nap of the cloth as to form bands of square blocks, alternating with plain vertical grooves, forming stripes or bands of stripes.

On reference to Figure 1 of the annexed drawing, which presents a face view of a piece of cloth finished according to my present design, it will be observed that this design is related to the one referred to, in that the grooves are arranged vertically at intervals to form plain vertical stripes or bands of stripes *a a*, between which are wider bands grooved in two directions to form blocked stripes or bands *b b*. It will be noted, however, that the crossed grooves in the bands *b b* are arranged diagonal to the plain vertical stripes *a a*, so as to produce lozenge or diamond shaped figures or squares with their sides diagonal to the vertical grooves of the stripes *a a*. I prefer the diamond-shaped figures shown with their long axis horizontal. I prefer to make the bands of vertical grooves and stripes *a a* much nar-

rower than the bands of diamond blocks *b b*; but the relative width of said bands may be varied without departing from the general effect of my design.

What I claim is—

1. The design for nap-surface of cloths, consisting of bands of diamond blocks alternating with plain parallel longitudinal stripes, substantially as herein set forth.

2. The design for the nap-surface of cloth, consisting of grooves disposed vertically at intervals to form bands of stripes, and intervening grooves crossing each other at an inclination to the former to produce bands of diamond-shaped blocks or diagonal squares alternating with the bands of stripes, substantially as herein set forth.

3. The design for the nap-surface of cloths, consisting of grooves disposed vertically at intervals to form plain stripes, alternating with grooves crossing each other at an inclination to the former to produce alternate bands of diamond blocks with their long axis at right angles to the grooves of the said stripes, substantially as herein illustrated.

4. The design for the nap-surface of cloths, consisting of vertical grooves disposed to form narrow stripes, alternating with wider bands crossed by inclined grooves in opposite directions to produce broad bands of diagonal blocks, contrasting with the narrow bands of stripes, substantially as herein shown and described.

FELIX SAMSON.
